United States Patent Office

Des. 230,108
Patented Jan. 29, 1974

230,108

DISPLAY STAND

James L. Sloan, Rochester, N.Y., assignor to Cross River
Products, Inc., Croton-on-Hudson, N.Y.

Filed Sept. 1, 1972, Ser. No. 285,731

Term of patent 14 years

Int. Cl. D6—06

U.S. Cl. D6—27

FIG.1

FIG.2

FIG.3

FIG.4

FIG. 1 is a front perspective view of a display stand showing my new design;

FIG. 2 is a top plan view on an enlarged scale;
FIG. 3 is a side elevational view thereof; and
FIG. 4 is a bottom plan view thereof.

I claim:

The ornamental design for a display stand, as shown.
